(57) **CLAIM**

We claim the ornamental design for the electric knife sharpener having a brushed textured housing, as shown and described.

DESCRIPTION

FIG. 1 is a left side elevational view of an electric knife sharpener having a brushed textured housing showing our new design;

FIG. 2 is a top plan view thereof;

FIG. 3 is a right side elevational view thereof;

FIG. 4 is a front elevational view thereof with the rear elevational view being identical; and,

FIG. 5 is a bottom plan view thereof.

The stipple shading is intended to represent an alternate surface material that is different from that of the areas that have straight-line shading.
